United States Patent Office

Des. 184,026
Patented Dec. 2, 1958

184,026

ROOM DIVIDER

Fred J. Piotraschke, Clayton, Mo.

Application May 22, 1957, Serial No. 46,291

Term of patent 3½ years

(Cl. D33—1)

Fig. 1

Fig. 2

Fig. 3

Figure 1 is a perspective view of a room divider incorporating the design of the instant invention.

Figure 2 is a top plan view of the room divider illustrated in Figure 1.

Figure 3 is a perspective view of the side opposite that illustrated in Figure 1.

I claim:

The ornamental design of a room divider, as shown.
